SEPARABLE SURGICAL STOCKING

James M. Bollinger, New York, N. Y.

Application August 8, 1940, Serial No. 351,844

2 Claims. (Cl. 128—165)

This invention relates to new and useful improvements in a separable surgical stocking.

The invention has for an object the construction of a surgical stocking which is characterized by a surgical stocking body for engaging about a leg and having an open side, and a fastener for closing said side.

Heretofore surgical stockings have been made continuous all around. Stockings of this type are very difficult to pull on. They must be constructed of elastic material sufficiently elastic to expand so as to allow the foot and portions of the leg to pass through. The provision of an open side and a fastener for closing the same produces a surgical stocking which may be engaged on and removed from a leg very readily.

Still further the invention contemplates a novel arrangement whereby the fastener comprises a slide fastener.

Still further the invention proposes another novel arrangement of fastener by which it is possible to vary the all around size of the stocking to recondition it after some use when the stocking body is slightly stretched.

For further comprehension of the invention, and of the objects and advantages thereof, reference will be had to the following description and accompanying drawing, and to the appended claims in which the various novel features of the invention are more particularly set forth.

In the accompanying drawing forming a material part of this disclosure:

Fig. 1 is a side elevational view of a surgical stocking constructed in accordance with this invention.

Fig. 2 is a horizontal sectional view taken on the line 2—2 of Fig. 1.

Fig. 3 is a fragmentary side elevational view of a surgical stocking constructed in accordance with a modified form of this invention.

Fig. 4 is a fragmentary enlarged horizontal sectional view taken on the line 4—4 of Fig. 3.

Fig. 5 is a fragmentary elevational view of a surgical stocking constructed in accordance with another form of this invention.

Fig. 6 is a fragmentary horizontal sectional view taken on the line 6—6 of Fig. 5.

The surgical stocking, in accordance with this invention, includes a surgical stocking body 10 for engaging about a leg such as schematically indicated by the dot and dash lines 11. The stocking body 10 has an open side 12. A slide fastener 13 is provided for closing the open side 12.

The slide fastener 13 comprises a stringer of

hooks 13^a mounted upon one side of the opening 12 and cooperative with a stringer of hooks 13^b mounted on the other side of the opening 12. A control slide 13^c is coactable with the hooks for engaging them together, and separating them, in the usual way. A back strip 14 is extended across the back of the slide fastener 13, and it is supported along one edge 14^a by a line of stitches 15.

Fig. 1 shows the surgical stocking on the leg 11. It may easily be removed by merely pulling the control slide 13^c downwards to open the slide fastener. This opens the side 12. It should be noted that the necessity of pulling the stocking body off the leg has been eliminated.

Figs. 3 and 4 disclose a modified form of the invention which distinguishes from the prior form in the provision of means for varying the all around size of the stocking body 10 to control the elastic stress of the stocking body on the leg. Specifically, one edge portion 12^a of the opening 12 is bent inwards. The stringer of hooks 13^a is mounted on the back side of the inwardly bent portion 12^a. At spaced positions along the inwardly bent portion 12^a there are fastening elements 15 which are cooperative with complementary fastening elements 15^a mounted upon the adjacent material of the stocking body.

The fastening elements 15 and 15^a comprise snap fasteners. Auxiliary complementary fastening elements 15' are arranged on the stocking body 10 at points spaced inwards from the opening 12, a larger distance than the complementary fastening elements 15^a. When the elastic body 10 becomes too loose it is possible to engage the fastening elements 15 with the auxiliary fastening elements 15'. In this way the all around diameter of the stocking body will be reduced. In other respects this form of the invention is similar to the previous form.

In Figs. 5 and 6 another form of the invention is disclosed which distinguishes from the prior forms in another construction for varying the all around size of the stocking body. In this form of the invention the stringer of hooks 13^a are connected by a lace 16 with a strip 17 secured along the stocking body 10 spaced inwards a material amount from the edge of the opening 12. The lace 16 has its ends 16^a tied together. The knot 16^a may be opened and the lace 16 drawn or let out so as to draw or let out the stringer of hooks 13^a. This controls the all around size of the stocking body. In other respects this form of the invention is similar to the previous forms.

While I have illustrated and described the preferred embodiments of my invention, it is to be understood that I do not limit myself to the precise constructions herein disclosed and the right is reserved to all changes and modifications coming within the scope of the invention as defined in the appended claims.

Having thus described my invention, what I claim as new, and desire to secure by United States Letters Patent is:

1. A surgical stocking body having an open side closed by means of a slide fastener, means adjacent one side of said slide fastener controlling the operative diameter of said stocking body to fit legs of different sizes, said stocking body having one edge of its open side bent inwards, said means, comprising a plurality of fastener elements arranged in vertically spaced rows on the inside face of said stocking adjacent said in-

wardly bent edge, and a vertical row of complementary fastener elements mounted on the adjacent face of said inwardly bent edge and selectively engageable with a row of said fastener elements.

2. In a surgical stocking body having a closable open side, said stocking body having one of its edges along its open side bent inwards, snap fastener elements arranged in vertical rows along the inside face of said stocking body adjacent said inwardly bent edge, and a vertical row of complementary snap fastener elements mounted on the adjacent face of said inwardly bent edge and selectively engageable with a vertical row of said first mentioned snap fastener elements for controlling the operative diameter of said stocking body.

JAMES M. BOLLINGER.
